UNITED STATES PATENT OFFICE.

FRANK A. HOLLENBECK, OF SYRACUSE, NEW YORK.

BREECH-LOADING FIRE-ARM.

SPECIFICATION forming part of Letters Patent No. 258,923, dated June 6, 1882.

Application filed January 27, 1882. (No model.)

To all whom it may concern:

Be it known that I, FRANK A. HOLLENBECK, of Syracuse, in the county of Onondaga, in the State of New York, have invented new and useful Improvements in Breech-Loading Fire-Arms, of which the following, taken in connection with the accompanying drawings, is a full, clear, and exact description.

This invention relates to certain novel devices for operating a three-barreled gun by only two locks and hammers, and also has reference to various improvements in the construction of breech-loading guns generally, and in the mechanisms essential to the successful operation of the same.

The invention is fully illustrated in the annexed drawings, wherein Figure 1 is a longitudinal section of my improved breech-loading fire-arm, the forward position of said section being taken along the side of the usual lug on the under side of the barrels, the rear part of the section being taken on the line parallel with the shifting-bar, which brings the firing-pin of the third barrel into operation with the hammer of the gun. Fig. 2 is a side view, showing the barrels in a tilted position. Fig. 3 is a transverse section on line xx . Fig. 4 is a face view of the breech of the barrels. Fig. 5 is a detached top view of the breech block or frame. Fig. 6 is a view of the under side of the barrels; Fig. 7, a transverse section of the barrels on line yy . Figs. 8 and 9 are enlarged detail views of the sight and its connection with the gun, and Fig. 10 illustrates modifications in the construction and arrangement of the shifting bar.

Similar letters of reference indicate corresponding parts.

B B designate the two shotgun-barrels, and C the rifle-barrel, secured to the under side of the former and midway between them. From the bottom of the barrel C project downward two lugs, i i' , the forward one, i' , of which is fitted to the hinge-pin F, which is secured to the forward extremity of the breech-extension G in the usual manner. The breech-extension G is provided with recesses I I', for the reception of the two lugs i and i' and the bottom portion of the rifle-barrel when the barrels are placed in their operative position on the breech-block or frame, as shown in Fig. 1 of

the drawings. By the engagement of the forward face of the lug i with the rear face of a bridge, L, on the breech-extension between the two recesses or mortises I and I' the recoil of the gun, when fired, is counteracted and the hinge-pin F relieved of the strain incident to the tendency of the separation of the barrels from the stock. To the sides of the bridge L is hinged a link, p, the free end of which has its cross-bar passing through an inclined slot, o, in the forward lug, i' . The slot o is extended through the rear end of said lug, and terminates with a notch, o', in the upper face of the lower portion of the slotted lug, as best seen in Fig. 1 of the drawings. In tilting the barrels, as shown in Fig. 2 of the drawings, the free end of the link is drawn toward the rear end of the slot o and drops into the notch o', thereby arresting the movement of the barrels and relieving the hinge of the barrels of the resultant strain.

E represents the extractor for the rifle-barrel C, said extractor having a forward-extended tongue, k', which slides in a longitudinal groove or channel, k, in the lugs i i' , and is of sufficient length to rest with its forward end against the cross-bar of the free end of the link p when said extractor is in its dormant position and the barrels brought down upon the breech-block or frame. The extractor is secured in the groove k by an extra plate, l, which is removably attached to the bottom of the lug i , so as to facilitate the construction and repairs of the groove constituting the guide for the extractor E. The tongue k' of the said extractor is provided with a longitudinal slot, m, through which passes a screw or pin, n, inserted transversely in the lug i , said pin serving to prevent the extractor from sliding out endwise and becoming lost when the barrels are detached from the stock. The slot m is of such a length as to allow the extractor E to be pushed rearward sufficient to carry the forward end of the tongue k' out of the lug i' , and thus allow the free end of the link p to be swung out of its engagement with said lug whenever it is desired to disconnect the barrels from the stock.

D represents the extractor for the shotgun-barrels B B, it consisting of a plate, h, adapted to engage the primed end of the cartridge

or shell, and having a forwardly-extended stem sliding in a channel in the metal between the two barrels B B. The extractor D is operated by the extractor E, which has a shoulder, g, engaging the rear of the plate h of the extractor D, and thus forces the same rearward or outward simultaneously with the rearward movement of the extractor E.

a and a' are the firing-pins for the respective barrels. Said firing-pins move in bushings t in the form of tubular plugs, which are screw-threaded externally, and inserted in correspondingly-threaded sockets or cavities u in the stock immediately back of the breech of the barrels. A collar, v, applied to the firing-pin at the forward end of the bushing t, in conjunction with said bushing, serves to prevent the escape of gas from the barrels when fired, and effectually excludes said gas from the mechanisms located in the stock.

s denotes a shifting-bar, which slides in a recess or chamber in the stock and lies across the rear end of the firing-pin of one of the shotgun-barrels and of the firing-pin of the rifle-barrel, said shifting-bar being provided with two apertures, r r', arranged in such relative positions that while one is in coincidence with its adjacent firing-pin the other aperture is normally out of coincidence with its respective firing-pin. The shifting-bar has a lateral as well as a sliding movement, and is by means of a spring, e, held normally in such a position as to bring the aperture r' of said bar in coincidence with the firing-pin of the rifle-barrel, and by means of springs e' and e'' pressing against the shifting-bar, respectively at the base and upper portion thereof, said bar is held yielding rearward, so as to allow the two firing-pins to be repelled back into the recoil-plate or breech-block by the rebound incident to the firing of the barrels.

Back of the upper end of the shifting-bar s, and in range with the firing-pin of the shotgun-barrel, is a plunger, b, provided with an axial cavity, c, adapted to receive the rear end of the aforesaid firing-pin, as hereinafter explained. The aforesaid position of the shifting-bars brings the solid portion thereof across the rear end of the firing-pin of the shotgun-barrel. Thus when the plunger b is struck by the hammer H said plunger throws the shifting-bar s forward, and the latter in turn propels the firing-pin of the shotgun-barrel and discharges said barrel, while the lower aperture, r', of the bar s allows the firing-pin of the rifle-barrel to pass through said aperture, and thus prevent the simultaneous firing of the rifle-barrel. The lower extremity of the shifting-bar s protrudes at the surface of the stock, and is provided with a suitable handle, by means of which said bar can be pushed inward, so as to bring the upper aperture, r, thereof in coincidence with the firing-pin of the shotgun and the solid portion of the bar below the lower aperture, r', across the firing-pin of the rifle-barrel. A shoulder, d, or other suitable catch

on the bar s, engaging with a shoulder on the inside of the stock, retains the said bar in its aforesaid position. If the gun is then fired, the firing-pin of the shotgun-barrel passes through the aperture r of the upper end of the shifting-bar and into the cavity c of the plunger b, thus leaving the charge of the shotgun-barrel undisturbed, while at the same time the solid lower portion of the shifting-bar forces the firing-pin of the rifle-barrel forward, and thus discharges said barrel. The forward thrust of the shifting-bars causes the shoulder d thereof to become disengaged, and so soon as this is effected the spring e forces the shifting-bar longitudinally and restores the same to the position for firing the shotgun-barrels, as before described.

In order to render the tripping of the shifting-bar adjustable, so as to change its position at the proper time, I apply to the exterior of the stock, and in close proximity to the shifting-bar, an eccentric screw or button, f, against which the lower extremity of said bar rests. By turning said screw the rearward thrust of the aforesaid portion of the shifting bar can be checked to increase or diminish the engagement of the shoulder d, as may be desired.

The plunger b is retained in the stock by means of a small screw, w, inserted through the side of the stock, and engaging with a longitudinal groove in the side of the plunger, as best shown in Fig. 1 of the drawings.

The rear end of the barrels is locked on the breech-block or frame by means of a lever, m, pivoted on top of the tang T in the manner hereinafter explained, said lever passing with its forward end through a laterally-enlarged channel, which is extended through the solid portion of the breech-block, and thus completely incloses said end of the lever m and effectually sustains the same to resist the upward strain when interlocked with the rear end of the barrels. The described channel allows the lever to swing laterally and engage a notch, N, in a rearwardly-extended hook, O, on the breech of the barrels, said hook entering a corresponding mortise in the upper part of the breech-block. The lever M, I provide with an eye, by which I pivot it on a cylindrical projection or boss, 1, on top of the tang T and integral therewith, in the center of which boss is a hole, 2, extending vertically through the tang. In this hole I insert the stem 3, which carries the sight 4, said stem being provided with a vertical slot, 5, through which passes a pin, 6, inserted through the side of the tang. Between the rear side of the stem 3 and the adjacent side of the hole 2, I place a spring, 7, which by frictional hold on the said stem retains the sight in its desired position. The upper end of the spring 7 is extended over the top of the boss 1 and over a portion of the lever M, and thus forms a key to hold the latter down upon the tang.

P represents the so called "fore-end" of the gun, and Q the tip-strap, which rests against

the forward end of the breech-extension G, and in conjunction with the bearing of the lug ν' against the hinge-pin F completes the connection of the barrels with the breech-extension. 5 Heretofore the fore-end and tip-strap were firmly united and operated as if formed in one piece. Consequently it was exceedingly difficult to render the same adjustable so as to compensate for the wear of the bearing of the tip-strap 10 on the end of the breech-extension, although it has been attempted to accomplish the said object by means of a spring pivoted on the combined tip-strap and fore-end, and bearing with its free end on a lug on the under side of 15 the barrels, yet the construction and arrangement of the spring were such that a slight wear of the parts threw the spring off its bearing on the lug and rendered the device inoperative. To overcome this difficulty I make the fore-end 20 and tip-strap in two separate parts, the fore-end being secured to the barrel by means of a forwardly-inclined shank, R, rigidly attached to the under side of the barrels, the fore-end being beveled to pass under the said shank, and secured thereto by a screw or screws passing through said parts. 25

The tip-strap consists of a metal block, fitted at its rear end against the forward end of the breech-extension, and having its forward end beveled to fit to the shank R aforesaid. In the top of the beveled end of the tip-strap there is a mortise, S, in which is placed a spring, U, in the form of a bow, which has its rear end hooked onto a hook, 8, in the rear end of the mortise. 30 The forward end of the spring U projects into a mortise in the shank R and in the fore-end, and is formed with a rearwardly-inclined or reversed curved face, V, which bears on a stud, 9, or other suitable shoulder in the mortise of the shank R, and thereby crowds the tip-strap upward against the said shank and rearward against the end of the breech-extension, and by the latter action causes the tip-strap to take up the lost motion incident to 45 the wear and abrasion of its joint with the end of the breech-extension. The free end of the spring U terminates with a rearward extension, 10, which passes underneath a cross-pin, 11, in the mortise of the tip-strap, and thus retains said spring in the mortise. The spring U has sufficient elasticity to allow the forward end of the tip-strap to be pulled out by applying the thumb of finger in a recess, 12, and against a lug, 13, on the under side of the tip-strap. The upper end of the shank R and the adjacent portion of the tip-strap are fitted to each other with a segmental face, 14, which is concentric with the hinge of the barrels, and at the said face there are two set-screws, 15, inserted into the tip-strap at opposite sides of 50 the rifle-barrel. By turning said set-screw so as to project from the tip-strap a greater or less distance, and thus press with greater or less force against the shank R, a positive adjustment of the connection of the tip-strap with the breech-extension is effected. 55

It is obvious that the herein-described shifting-bar s can be arranged in various ways, and I therefore do not limit myself in that respect. One of the modifications of the construction 70 and arrangement of the shifting-bar is illustrated in Fig. 10 of the drawings, and consists in terminating said shifting-bar inside of the breech-block and connecting thereto a pivotal lever, 16, which projects through the side of 75 the breech-block. By depressing the outer end of said lever the shifting-bar is moved upward to bring the solid lower portion thereof over the firing-pin of the rifle-barrel, and simultaneously bring the aperture in the upper end 80 of said bar in coincidence with the firing-pin of the shotgun-barrel. A reverse movement of the lever 16 restores the shifting-bar into its position for liberating the firing-pin of the rifle-barrel and for firing the shotgun-barrel. 85

Having described my invention, what I claim as new, and desire to secure by Letters Patent, is—

1. The combination of the tang T, provided with the boss 1 and vertical hole 2, the lever 90 M, pivoted on said boss, the sight 4, having the stem 3 in the hole 2, and the spring 7 at the side of the stem and overlapping the top of the lever, all combined and arranged as shown and set forth. 95

2. The combination of the tang T, provided with the vertical hole 2, the sight 4, having the stem 3, provided with the slot 5, and the connecting-pin 6, substantially in the manner described and shown. 100

3. The combination, with a three-barreled gun, of a shifting-bar arranged across the rear end of the firing-pins and provided with passages for the firing-pins, arranged in such relative position that while one of said passages 105 is brought in coincidence with a firing-pin the other is normally out of coincidence with its respective firing-pin.

4. In combination with the barrels B C, their firing-pins a and a' , and the hammer H, the shifting-bar s arranged across the end of said firing-pins, having the apertures r and r' , arranged as described, and the plunger b , provided with the cavity c , as set forth and shown. 110

5. In combination with the barrels B C, their firing-pins a and a' , and the hammer H, the shifting-bar s , provided with apertures r and r' and with the catch or shoulder d , the springs e e' e'' , and the plunger b , provided with the cavity c , substantially as and for the purpose 120 specified. 115

6. In combination with the shifting-bar s , provided with the shoulder d , and arranged so as to be movable laterally in the stock, as shown, the eccentric screw or button f , as and 125 for the purpose specified.

7. The combination and arrangement, with the two barrels B B, situated side by side, of the third barrel, C, placed beneath the former and central between them, and the extractor 130 E, arranged beneath the third barrel and adapted to engage the cartridge or shell in the bar-

rel C, and to actuate simultaneously the extractor of the barrels B B, substantially as described and shown.

8. The combination, with the two barrels B B, situated side by side, of the third barrel, C, placed beneath the former and central between them, the extractor E, adapted to engage the cartridge or shell of the barrel C, and provided with the shoulder g, and the extractor D, having the plate h in front of said shoulder, substantially as described and shown, for the purpose set forth.

9. In combination with the three barrels B B and C, arranged as described, the lug i, projecting from the bottom of the barrel C, and provided with the channel k, the extractor E, having the tongue k' in said channel, and the plate l, detachably applied to the bottom of the said lug, as and for the purpose set forth.

10. In combination with the barrels B B and C, the lugs i i', having the channel k and inclined slot o, with notch o', the extractor E, having the tongue k' in said channel, and provided with the slot m, the pin n, and the link p, hinged on the bridge L and having its free end in the slot o and engaging the front end of the extractor, all constructed and combined in the manner shown and set forth.

11. The combination of the fore-end P, forwardly-inclined shank R, tip-strap Q, having a beveled forward end, and the spring U, as and for the purpose set forth.

12. In combination with the fore-end P and breech-extension G, the forwardly-inclined shank R, provided with the segmental face 14, 35 the tip-strap Q, fitted to the shank and having a corresponding segmental face, and the set-screw 15, inserted in the tip-strap at said face, substantially as and for the purpose set forth.

13. The combination of the forwardly-inclined shank R, fixed to the barrel and provided with a mortise, and with the stud 9 in said mortise, the fore-end inserted under said shank, the tip-strap Q, having a beveled forward end and provided with the mortise S, and with the pin 11 and hook 8 in said mortise, and the spring U, connected to the hook 8 and having at its forward end the reversed curved face V, bearing on the stud 9, and its extremity 10, extended underneath the pin 11, all constructed and combined substantially in the manner described and shown, for the purpose set forth.

In testimony whereof I have hereunto signed my name and affixed my seal, in the presence of two attesting witnesses, at Syracuse, in the county of Onondaga, in the State of New York, this 28th day of December, 1881.
